UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

HINGE.

Original application filed March 24, 1922, Serial No. 546,232. Divided and this application filed May 21, 1924. Serial No. 714,848.

To all whom it may concern:

Be it known that I, STUART W. PARSONS, a citizen of the United States, and a resident of New Britain, county of Hartford, State 5 of Connecticut, have invented certain new and useful Improvements in a Hinge, of which the following is a specification.

The aim of the present invention is to provide a hinge for use on trunks and the like, 10 and having various features of novelty and advantage, and, more particularly, to provide a hinge of this sort which is very simple in construction and therefore may be economically manufactured, and which is 15 very sturdy in that it is enabled to resist comparatively great strains and stresses placed upon it.

This application is a divisional of my application Serial No. 546,232, filed March 24, 20 1922.

In the accompanying drawings, wherein I have shown for illustrative purposes two embodiments which the present invention may take;

25 Figure 1 is a plan view of my improved trunk hinge;

Fig. 2 is an edge view thereof with the leaf *a* partially in longitudinal section;

Fig. 3 is a detail view in edge elevation 30 with the end of the pintle cut away to show the manner in which the pintle is held against rotation relative to one of the leaves;

Fig. 4 is a blank from which the leaf *a* of the hinge shown in Fig. 1 is formed;

35 Fig. 5 is a view similar to Fig. 1 but showing another embodiment of the invention;

Fig. 6 is a perspective view of the parts 40 of the hinge of Fig. 5; and

Fig. 7 is a sectional view taken on line 45 7-7 of Fig. 5.

Referring to Figures 1 to 4, inclusive, *a* and *b* denote the respective leaves of a trunk hinge, and *c* designates the pintle pivotally connecting the leaves together. Each of the 45 leaves is preferably constructed of sheet metal by stamping out a blank to the desired configuration and then drawing or pressing the blank to the required form. The leaf *b* has a knuckle 10 formed integral therewith by rolling the metal upon itself. This knuckle preferably rises above the plane of the body portion of the leaf *b*. The leaf is provided with the longitudinally extending

corrugation 12, having one end merging into and formed integral with the knuckle 10. 55 This corrugation 12 constitutes a reinforcing rib which prevents longitudinal flexure of the body portion of the leaf and also serves to strengthen the knuckle 10, anchoring and bracing it, as it were, against distortion and 60 bending, and particularly at its juncture with the body portion of the leaf.

One end of the leaf *a* is upturned, thus providing a wall 15, which is upset or inclined to the plane of the leaf *a*. This wall 65 forms a socket, so to speak, for the reception of the knuckle 10 of the leaf *b*. At each end of the wall or flange 15 and formed integral therewith is an apertured projection 16, these 70 projections being bent down at right angles to the leaf *a* so as to constitute the knuckles or bearings between which the knuckle 10 is interposed. The pintle *c* is positioned and 75 suitably secured in the aligned apertures or openings in the knuckles. The leaf *a* is provided with a longitudinally extending, reinforcing rib 18, similar to the rib 12 of the leaf *b*. This rib 18, at its inner end, merges into and is integral with the inclined wall 15. The edge of the wall 15 may be recessed 80 as at 20 and the edge of this recess constitutes a shoulder or abutment which is adapted to engage, as shown by dotted lines of Fig. 2, against the rib 12 of the leaf *b*, and thus limit the extent to which the leaves may 85 be swung relative to one another. It will be seen that since the projections or knuckles 16 are at right angles to the plane of the leaf *a* and to the length of the pintle *c*, the strains on these knuckles are in the direction 90 of their planes. These knuckles are integral with the wall 15 of the leaf *a*, and this wall is strengthened, anchored and braced by the rib 18. All of which means that an extremely strong structure is provided, the parts of 95 which are well enabled to serve a relatively heavy duty, and particularly to resist strains to which they are subjected when the hinged member is thrown into full open position bringing the abutment 20 into engagement 100 with the rib 12. The pintle *c* has a comparatively long and, therefore, a very substantial bearing in the knuckle of the leaf *b* and comparatively short bearings in the openings provided in the knuckles 16. In order 105 to eliminate excessive wear, the pintle is held

against rotation in suitable manner relative to the knuckles 16 while the leaf *b* is adapted to swing relative to the pintle. To this end the pintle opening 21 in one of the knuckles 16 is noncircular, and that portion of the pintle positioned in this opening is of similar cross-section, thus preventing rotation between knuckles 16 and the pintle. In the present instance, the wall of the opening 21 in the knuckle is notched, as at 22, and the pintle is expanded into this notch, so that the pintle and knuckle are in interlocked engagement.

Referring now to the embodiment shown in Figs. 5 to 7, inclusive, the leaves *a'* and *b'* are preferably formed of sheet metal as in the preceding embodiment. The leaf *b'* has two alined knuckles 10', 10', formed by rolling the metal back upon itself, and each rising above the plane of the leaf. Merging into each of the knuckles 10' and extending longitudinally of the leaf is a corrugation 12'.

The leaf *a'* has an end wall 15' forming a socket for the knuckles 10', and this end wall is reinforced by a pair of corrugations 18'. At each end of the wall or flange 15' is an apertured projection 16' corresponding in construction and arrangement to the knuckles or bearings 16 of the preceding embodiment. The leaf *a'*, in addition to the end knuckles 16', is provided with a pair of intermediate knuckles 30 formed integral with a portion 31 extending from the end wall 15' and located centrally thereof. In forming the leaf *a'* a blank is stamped out with the extending portion 31 provided at each end with an ear. The blank is then pressed to shape with the ears bent down at right angles to the body portion of the extension 31 so as to form the knuckles 30. It will be seen from the drawings that the portion 31 is adapted to fit in between the knuckles 10' of the leaf *b'*. The pintle 21 is held against rotation in the apertures of the knuckles 16 and 30 as, for instance, by

notching one of the knuckles as at 22, and expanding the pintle into the notch.

It is, of course, obvious that the invention is susceptible of various modifications and changes which are within the spirit of the invention without departing from the scope of the following claims, it being understood that the present disclosure of the invention is by way of illustration only and it is not to be taken as restrictive of my conception.

I claim as my invention:

1. A hinge of the character described comprising a pair of leaves constructed of sheet metal, one of said leaves having a knuckle above the plane of this leaf and formed by rolling one end of the leaf onto itself, and a longitudinally extending corrugation merging into the wall of said knuckle adjacent the top thereof; the other of said leaves having an up-turned flange at one end integral therewith, projections constituting knuckles integral with the side edges of said flange and disposed at right angles thereto, and a longitudinally extending corrugation alined with said first corrugation and merging into and rising substantially to the top of said flange.

2. In a hinge of the character described comprising a pair of leaves constructed of sheet metal, one of said leaves having a pair of knuckles formed by rolling one end of the leaf onto itself, and a pair of longitudinally extending corrugations respectively merging into the knuckles; the other of said leaves having an upturned flange at one end integral therewith, projections constituting knuckles integral with the side edges of said flange and disposed at right angles thereto, a portion extending centrally from said flange and having end portions bent down at right angles to form knuckles in alinement with said projections, and a corrugation merging into said flange; and a pintle extending through said knuckles for holding the parts together.

STUART W. PARSONS.
